[57] **CLAIM**

The ornamental design for a diagnostic scanner control console, as shown and described.

DESCRIPTION

FIG. 1 is a top plan view of a diagnostic scanner control console showing our new design;

FIG. 2 is a front elevational view thereof;

FIG. 3 is a left side elevational view thereof;

FIG. 4 is a right side elevational view thereof;

FIG. 5 is a rear elevational view thereof; and,

FIG. 6 is a bottom plan view thereof.

The broken lines shown in FIGS. 2, 3, 4 and 5 are for illustrative purposes only and form no part of the claimed design.

FIG. 1

FIG. 2

FIG. 3

FIG. 4

FIG. 5**FIG. 6**
